UNITED STATES PATENT OFFICE

CARL H. LARSSON, OF CHICAGO, ILLINOIS

VALVE TONE THROAT

Application filed February 15, 1929. Serial No. 340,304.

This invention relates to means for transmitting sound from a plurality of sources to a common outlet or loud speaker and selective means whereby any one of said sources may be placed in communication with the outlet. More specifically, it provides a plurality of passageways or tone throats through a substantially solid medium with a rotatable apertured member for connecting either of said 10 passageways with a common outlet and by this means I provide an arrangement whereby communication may be made, for instance, from a phonograph tone arm or a radio reproducer element to a loud speaker or amplifying chamber.

The objects of this invention are to provide a combined radio and phonograph with means whereby either may be connected with a tone amplifier; to provide a device of this 20 character in which passageways are provided from the respective tone producers to a common outlet, and a rotatable element is utilized for completing the connection from one element or the other to such common outlet; to 25 provide novel actuating means for rotating the element used for switching from one tone producer to another; and to provide such other novel features and improvements in construction as will be described more fully 30 hereinafter.

In the accompanying drawings illustrating this invention,

Figure 1 is a plan view of a combined phonograph and radio instrument with my 35 improved valve or switch device applied thereto;

Figure 2 is a vertical sectional view taken on the line 2—2 of Figure 1;

Figure 3 is an enlarged sectional view showing 40 one form of valve throat with communication established between the radio and the loud speaker.

Figure 4 is a view similar to Figure 3 showing the valve or switch turned to provide communication between the phonograph and the 45 loud speaker;

Figure 5 is a sectional view taken on the line 5—5 of Figure 2;

Figure 6 is a sectional view similar to 50 Figure 3 showing a modified form of con-

struction in which the radio and phonograph throats or passageways are arranged on either side of the common outlet; and

Figure 7 is a view similar to Figure 6 showing the valve turned to provide communication from the phonograph to the loud speaker.

The cabinet 8 as shown in these drawings may be of any ordinary or preferred form of construction and is provided adjacent to the 60 top with a partition 9 having a hole 10 through which projects the upper end or throat 11 of a tone amplifier or loud speaker, a portion thereof being shown at 12. A rectangular block 13 is secured to the partition 9 65 and is of sufficient size to permit the forming of the necessary channels or throats therethrough and the mounting of the switching or valve element therein. The top 14 of the cabinet 8 engages with the block 13 and 70 carries the phonograph and radio reproducing mechanism. The phonograph turn table 15 may be driven by any suitable mechanism, as indicated at 16, and the phonograph tone 75 arm 17 is pivotally mounted at 18 on the top 14, the top being provided with a hole 19 in alignment with the tone arm. The radio reproducer or loud speaker element 20 is also mounted on the top 14, a convenient arrangement being the insertion of the outlet tube 21 80 in a hole 22 in the top.

As shown particularly in Figures 3 to 5, a channel or throat 23 in the block 13 leads from the hole 19 and is adapted to be connected at times with a common outlet channel or throat section 24 at the bottom of the block which connects with the throat 11 of the amplifier or loud speaker. Another channel or throat 25 leads from the hole 22 through the block 13 and is also adapted to be connected at times with the outlet opening 24.

The throats or passageways 23 and 25 lead to one side of a circular hole or valve chamber 26 which extends through the block 13 and which is provided with a rotatable valve 27 which is mounted to turn therein. This valve has a transaxially formed throat section or passageway 28 in one side thereof which is adapted to complete the communication from the phonograph through the 100

block and adjacent parts to the loud speaker. The valve member 27 is also provided on the opposite side with a recess or passageway 29 which is adapted to be turned to register with the radio throat or passageway 25, as shown particularly in Figure 3 in order to complete the throat or opening from the radio to the amplifier or loud speaker. It will be noted that the throats or passageways from the tone arm and from the radio to the loud speaker are of gradually increasing cross section throughout their length which prevents any restriction of the tones and which tends to increase the volume of the sound passing therethrough. Furthermore, these passageways or channels are formed through substantially solid or rigid members so that there is little or no possibility of the tones being distorted or marred by undue vibration or by any rattling parts.

The rotatable valve member 27 may be supported and turned in any suitable manner but is preferably provided with pivots or trunnions 30 and 31 which engage with bearings 32 which are secured in plates or side pieces 33 which are secured to the block 13 and which cover the ends of the hole 26 in which the valve is mounted. The trunnion 30 is provided with a worm wheel 34 which is engaged by a worm 35 on a shaft 36 which is mounted in bearings 37 and which extends out through one side of the cabinet, as shown in Figure 2, where it is provided with a handle or wheel 38 for turning the same. A stop finger 39 is secured to the wheel 34 and engages with stop pins 40 and 41 to limit the turning movement of the valve so that the passageways therethrough will be brought into exact alignment with the respective phonograph and radio throat channels through the block.

The operation of this device is substantially self-evident, as by turning the wheel or handle 38 the valve or switch member 27 may be turned to bring the passageway 28 into alignment with the hole 23 for the phonograph output or may be turned to bring the passageway 29 into alignment with the passageway 25 for the radio output.

Due to the different types of construction of phonographs and cabinets, there may be considerable variation in the location of the tone arm and radio element so that it is not always practicable to have both of these located on one side of the valve, as shown in Figure 3, but they may be located in any desired position with respect thereto. In the modified form of construction shown in Figures 6 and 7, the radio inlet opening 42 is located on one side of the valve member, and the phonograph inlet opening 43 is located on the opposite side of the valve member 44. The radio throat or passageway 45 leads from the opening 42 and registers at times with the throat section or passageway 46 in the valve

member 44 which in turn leads to the outlet 47. The phonograph throat or passageway 48 registers at times with the throat section 49 through the valve 44, the opposite end of which also registers at times with the outlet 47 which leads to the loud speaker throat 11; otherwise the construction and operation of this form is substantially the same as the one heretofore described, but it will also be noted that a gasket or washer or resilient material 50 may be interposed between the end of the throat 11 and the block in order to make a tight closure and to prevent any possibility of vibration or rattling at this point.

From this description it will be seen that I provide a novel apparatus for use in connection with combined phonographs and radios whereby the loud speaker or amplifier may be connected with one or the other. Furthermore, the passageways thus provided are in the nature of throats and so proportioned as to transmit the sound in the best manner possible.

Having thus described my invention, which, however, I do not wish to limit to the exact arrangement herein shown and described, except as specified in the following claims, what I claim and desire to secure by Letters Patent is:

1. In a device of the character set forth, the combination of a phonograph tone arm, a radio reproducer, a loud speaker adapted to project tones from said tone arm or said reproducer, a block rigidly mounted between the tone arm and reproducer and the loud speaker, passageways leading from the tone arm and reproducer respectively through said block to the loud speaker, a rotatable valve for controlling said passageways, a gear secured to said valve, a second gear engaging with said gear, a shaft on which the second gear is mounted, and means for turning said shaft.

2. The combination with a cabinet, of a loud speaker mounted therein and having an inlet throat, a valve body mounted above the inlet throat and having an outlet connected therewith, a phonograph tone arm mounted adjacent to said body, a passageway leading from the tone arm through the body to said outlet, a radio reproducer also mounted adjacent to said body, a passageway leading from said reproducer through said body to said outlet, a valve for controlling said passageways, means for turning the valve, and means for stopping the valve when its ports register with the respective passageways.

3. The combination of a cabinet, a partition in said cabinet, a tone amplifier mounted in the cabinet and having an inlet projecting through said partition, a block mounted above the partition, a top for the cabinet above said block, a phonograph mounted on said top and having its tone arm rotatably

mounted in the top above the block, a radio reproducing element mounted in the top above the block, tone throats of increasing diameter leading from the tone arm and the reproducer element respectively through the block to the inlet of the tone amplifier, a circular body rotatably mounted in the block and having tone throat sections therethrough adapted to register at times with said tone throats, 5 said tone throat sections increasing in diameter to conform to said tone throats, and means for rotating said circular body.

4. In a device of the character set forth, the combination of a block having two passageways leading from separate inlets to a common outlet, said block having a cylindrical hole therethrough which intercepts said passageways, a cylindrical rotatable member mounted in said hole and extending through 10 the block, said member having openings for establishing communication at times from the respective passageways to the outlet, sides secured to said block and covering the ends of said hole, trunnions for said rotatable 15 member, bearings in said sides for said trunnions, a worm gear secured to one of said trunnions, a worm engaging with said gear, a rod on which said worm is mounted, bearings for said rod, a handle for turning 20 the rod, an arm secured to said worm gear and stops adapted to be engaged by said arm to limit the movement of said rotatable member.

5. In a device of the character set forth, the combination of a solid block formed of wood or the like having tone throats leading from separate inlets to a common outlet, a rotatable member in said block coacting with said throats and having throat sections there- 25 through which form sections of the first named throats, the arrangement being such that when the rotatable member is turned to one position communication through one of said throats will be established and when 30 the rotatable member is turned to another position, communication through the other throat will be established, said throats being of gradually increasing cross section, substantially as described.

CARL H. LARSSON.
